UNITED STATES PATENT OFFICE.

CHRISTIAN G. SINGLEY, OF MANHEIM, PENNSYLVANIA.

CIGAR-CRIMPER.

No. 894,858.

Specification of Letters Patent.

Patented Aug. 4, 1908.

Application filed July 2, 1907. Serial No. 381,930.

To all whom it may concern:

Be it known that I, CHRISTIAN G. SINGLEY, a citizen of the United States, residing at Manheim, in the county of Lancaster and 5 State of Pennsylvania, have invented new and useful Improvements in Cigar-Crimpers, of which the following is a specification.

This invention relates to an improvement in cigars of that class in which a metallic 10 thimble of the required shape and size is used for the purpose of crimping the wrapper on the head end thereof, when forming said head end. In said thimble is arranged an axial pin, being rigidly affixed or loose. 15 When said pin is loose, it is movable, longitudinally in and out, for the purpose of forming an axial hole in said head end, and the pin is surrounded on the inner side of the thimble with a coiled spring, for the purpose 20 of withdrawing the same after said hole has been formed.

The object of the invention is to provide a simple device for use in the manufacture of the cigar, whereby a hole may be made in the 25 end of the cigar and the edge of the wrapper crimped over into said hole by revolving said device upon the end of the cigar in the process of manufacture.

The purposes of the invention are attained 30 by the mechanism, devices and means illustrated in the accompanying drawing, in which similar reference characters are used to designate like parts throughout the several views, in which:—

35 Figure 1, is a sectional view of a thimble showing the details of construction. Fig. 2, is a side elevation, partially in section of a cigar with the thimble in place showing the method of operating. Fig. 3, is an end view 40 of the thimble showing the head of the plunger. Fig. 4, is an end view of the thimble showing the bell-shaped mouth.

In the drawing A designates a cigar of the character referred to in the opening paragraph hereto; in which the head end *a* appears in longitudinal vertical section and in which B designates a thimble, having a rigidly affixed longitudinal pin *b* at the center thereof, for the purpose of forming a longitudinal hole in the head end of the cigar 45 when the wrapper is crimped thereon (see Fig. 2).

A¹ designates a cigar with its head end *a*¹ appearing in longitudinal central section and 50 in which B¹ designates a thimble affixed on

said head end, for the purpose of crimping the wrapper thereon, and b¹ designates a longitudinal pin having a button b² on the left hand end thereof, for the purpose of pushing said pin into the axis of the head 60 end of the cigar, forming a longitudinal hole therein.

C designates a coiled spring surrounding the pin on the inner side of the thimble, for the purpose of withdrawing the pin after 65 said longitudinal hole has been formed (see Fig. 4).

A² designates a cigar with its head end *a*² appearing in longitudinal central section, and in which B² designates a thimble affixed 70 on said head end, for the purpose of crimping the wrapper thereon, and b³ designates a longitudinal pin having a button b⁴ on the left hand end thereof, for the purpose of pushing said pin into the axis of the head end 75 of the cigar, forming a longitudinal hole therein.

C¹ designates a coiled spring surrounding the pin on the outer side of the thimble, for the purpose of withdrawing the pin after 80 said longitudinal hole has been formed (see Fig. 6).

It will here be remarked that the coiled spring C surrounding the pin *b*¹ has its upper end in engagement with the under side of a 85 collar b⁵, for the purpose of withdrawing said pin *b*¹, while a stop-pin b⁶ is secured into the upper end of the thimble B¹, for the purpose of checking the withdrawal of said pin *b*¹ at that point. At the required point on opposite sides near the upper end of the thimble B² are two pins b⁷ b⁷, one situated above the other. Between said lower pin b⁷ and the button b⁴ of the longitudinal pin *b*³ the spring C¹ is compressed, while these pins b⁷ b⁷ by 95 engagement with the collar b⁸ serve to check the withdrawal of said pin *b*³ when the axial hole in the cigar head is completed.

The invention having thus been ascertained and described in the manner in which 100 its functions are performed fully shown and set forth, what is considered new and desired to be secured by Letters Patent is:—

In a cigar crimper of the class described, a thimble formed with a bell-shaped opening 105 in one end, and a tubular opening in the other end; said openings connected by an axial longitudinal hole; a finger-plunger pointed at one end and headed at the other end, and slidably mounted within said hole 110

and tubular opening: a coiled spring embracing said pin and contained within said tubular opening: a locking pin extending transversely through said thimble near said tubular opening, all for the purpose of crimping a cigar end during the manufacture thereof.

In testimony whereof I affix my signature, in presence of two subscribing witnesses.

CHRISTIAN G. SINGLEY.
